UNITED STATES PATENT OFFICE.

HERMAN R. BLICKLE, OF PITTSBURGH, PENNSYLVANIA.

BUILDING CONSTRUCTION.

1,371,727.

Specification of Letters Patent. Patented Mar. 15, 1921.

Application filed November 23, 1918. Serial No. 263,844.

To all whom it may concern:

Be it known that I, HERMAN R. BLICKLE, a citizen of the United States, residing at Pittsburgh, in the county of Allegheny and 5 State of Pennsylvania, have invented certain new and useful Improvements in Building Construction, of which the following is a specification.

My invention consists of an improvement 10 in building construction, more especially of structural formation, utilizing special shapes of rolled or pressed metal to carry out the desired functions of the invention.

In the manufacture of steel frame buildings and the like, commercial rolled shapes such as I-beams, channels, angles, etc., are customarily used, frequently in connection with concrete flooring, and various arrangements of these materials have been utilized 20 in many different ways.

My invention has in view to arrange metallic elements, of novel construction, in such a manner as to provide ample strength and resisting stability to the loads and 25 strains, with accompanying advantages in locating covering and supporting members providing for the application and support of concrete bodies as for floors; the covering of the lower portion of the construction 30 as for ceilings; the provision of ample interior space for the housing of pipes, wires, etc.; and generally to provide a completely efficient mechanical construction having these and the usual attributes and advantages 35 commonly present in structural forms.

Referring to the drawings, which illustrate certain adaptations of the invention and certain preferred forms of construction,

Figure 1 is a vertical sectional view 40 through a portion of a floor construction utilizing my invention;

Fig. 2 is a detail perspective view of one of the main structural beam members;

Fig. 3 is a similar view showing a modified construction;

Fig. 4 is a view similar to Fig. 1 showing the construction as embodied with a column or post; and

Fig. 5 is a perspective detail view showing 50 a portion of one of the covering plates.

The principal novel member of the improvement consists of a channel or C-shaped member of rolled or pressed steel having a web 2, upper and lower flanges 3, 3, and 55 inwardly turned terminal flange webs or lips 4, 4. Such member is designed to be

used either alone; or with another similar beam member in the manner indicated in Fig. 1, in which case, the main web members, set back to back, are preferably secured together as by rivets 5.

When so combined, the two C-shaped members generally approximate an I-beam in form and in resulting strength and stability, with the material additional advantage of the stiffening effect of the inwardly turned flange webs 4. These flange webs, which may be of any desired depth, provide supplemental trusses for the structural member itself at one side, and for the combined I-beam shaped member when connected, at both sides. The supporting strength of the beam is thereby greatly increased and its rigidity is stiffened, flange webs 4 acting against either compressive or tensile 75 strains in the same general manner as the web member 2.

A further additional and material advantage is that the terminal inturned flange webs 4 provide very efficient anchoring extremities for the application and fixed support of the ceiling plates and floor plates in the manner illustrated in Fig. 1. Such plates 6, which are preferably of rolled or pressed metal, are provided with laterally 80 extending ribs 7 intermediate of their width extending across the full length of the plates adjacent each side edge portion, and are so positioned with relation to the center dimensions of the several beams that they will 85 fit snugly in place, with the flanges 7 extending inwardly along the adjacent faces of beam flange webs 4. When used in this manner for the purpose of floor plates, the edges of adjacent plates meet, as at 8, at 90 the center of the compound beam members, thus providing continuous supporting surfaces upon which may be laid concrete or other flooring material 9.

When used as ceiling members, plates 6 100 are applied underneath the beams in the same manner and the flanges 7 are turned over into fixed holding engagement with flange webs 4, as indicated in Fig. 1. By this means the floor plates above are fixedly 105 held in operative position and relation to the floor beam members, while the ceiling plates are suspended tightly up against the lower flange portions 3 of the beam members and provide continuous smooth ceiling 110 surfaces which may be utilized in such form, or may be covered with any addi-

tional material. If desired, plate 6 may be perforated or slotted and elongated, providing anchoring openings for plaster or the like.

5 If desired, the projecting securing portions 7 of plates 6 may be cut out at intervals, as indicated at 10, providing series of alternating projecting lips 11 which may be easily bent over the flange webs 4, one at a 10 time, by hammering, swaging or otherwise, or the entire continuous edge portion of projection 7 may be preliminarily bent over and slid into position, after which its inner edge may be bent down into holding 15 engagement with flange webs 4, as will be readily understood. With either construction, the engagement is positive, enduring and reliable, and will insure continuous efficiency of the structure.

20 When desired, the C-shaped member may be pressed into the form shown in Fig. 3, in which case, the lower flange member 3^a is bowed downwardly at its middle portion, increasing the depth and resulting resisting 25 strength of the web portion 2^a in the manner of a truss, in which case, the ceiling plates would be also bowed around correspondingly, or supported in continuous flat formation by providing suitable lengths of 30 attaching terminals 11. Either straight beams or bowed beams may be utilized with the floor and ceiling members in the same general manner.

One utilization of the C-shaped beam 35 alone is illustrated in Fig. 4, in which case, the web 2^b is riveted or bolted directly against the face of a post or column member 12 of I-beam, channel, or other suitable shape, or the C-shaped member, either single or double, may be used as a column 40 itself, the floor and ceiling plates 6^a and 6^c respectively being secured in position in the same manner as above described.

By my improved construction I avoid the 45 necessity of any preliminary false work or shoring for supporting the flooring in the course of laying or formation, as the upper floor plates provide ample strength and area so that the flooring may be laid thereon directly.

Other applications, connections, or utilizations of the invention may be readily made by the builder or designing engineer, and it may be applied to various and widely different 55 combinations with other material, and in the fabrication and erection of variously different structures, without departing from the invention or the scope of the following claims.

60 What I claim is:

1. In combination, a structural member of rolled or pressed metal having a middle web portion and lateral top and bottom flange members, and a plate member laid against 65 one of said flange members and having an

integral projecting portion engaging the flange terminal.

2. In combination, a structural member of rolled or pressed metal having a middle web portion and lateral top and bottom flange members, the lower flange being downwardly arched, and a plate member laid against one of said flange members and having an integral projecting portion engaging the flange terminal. 75

3. In combination, a pair of rolled or pressed structural members having web portions secured together back to back, and having laterally extending top and bottom flange members, and a plurality of co-acting 80 plate members laid against one of said flange members and having an integral projecting portion engaging the flange terminal.

4. The combination with a rolled or pressed structural member having a middle 85 web portion and top and bottom laterally extending flange members provided with inwardly turned web members, of a floor plate resting upon the upper flange member and provided with a downwardly extending portion 90 engaging against its inwardly turned web terminal member.

5. The combination with a rolled or pressed structural member having a middle web portion and top and bottom laterally extending flange members provided with inwardly turned terminal web members, of a ceiling plate having an upwardly extending portion 95 bent over into holding engagement with the lower inwardly turned terminal web 100 member.

6. The combination with a rolled or pressed structural member having a middle web portion and top and bottom laterally extending flange members provided with inwardly turned web members, of a floor plate resting upon the upper flange member and provided with a downwardly extending portion 105 engaging against its inwardly turned web member, and a ceiling plate having an upwardly extending portion bent over into holding engagement with the lower inwardly turned terminal web member.

7. In building construction, the combination with two parallel beam members 115 each having a web portion and upper and lower flange portions provided with inwardly turned web member terminals, of a connecting floor plate laid across from one beam member to the other resting on their upper flanges and having downwardly extending flanges confronting their web member terminals, and an upper flooring thereon. 120

8. In building construction, the combination with two parallel beam members each having a web portion and upper and lower flange portions provided with inwardly turned web member terminals, of a connecting floor plate laid across from one beam member to the other resting on their upper 125 130

flanges and having downwardly extending flanges confronting their web member terminals, an upper flooring thereon, and a similar ceiling plate having upwardly extending flange portions bent over into holding engagement with the lower inwardly turned web member terminals.

9. A covering floor or ceiling plate having integral holding portions extending at right angles to the plate intermediate of its width and adjacent its opposite edges.

10. A covering floor or ceiling plate having integral holding portions extending at right angles to the plate intermediate of its width and adjacent its opposite edges and 15 provided with a series of projecting holding terminals adapted to be bent over into hooked form.

In testimony whereof I hereunto affix my signature.

HERMAN R. BLICKLE.
